UNITED STATES PATENT OFFICE.

HENRY F. RENNER, OF ERIE, PENNSYLVANIA, ASSIGNOR TO THE HOLLANDS MANUFACTURING COMPANY, OF SAME PLACE.

DESIGN FOR A VISE-JAW.

SPECIFICATION forming part of Design No. 34,030, dated February 5, 1901.

Application filed December 21, 1900. Serial No. 40,693. Term of patent 14 years.

To all whom it may concern:

Be it known that I, HENRY F. RENNER, a citizen of the United States, residing at Erie, in the county of Erie and State of Pennsylvania, have invented and produced a certain new and original Design for Vise-Jaws; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

In the drawings illustrating my design, Figure 1 is a side view in elevation of a vise-jaw embodying my design. Fig. 2 is a vertical longitudinal section of the same. Fig. 3 is an end view of the same.

The leading feature of my design consists substantially in the shape and configuration of the jaw, which slides back and forth in an opening in a vise-frame.

In the drawings, A is the jaw, and B the

arm, which extends into an opening in a vise-frame. The arm B is a hollow shell, in cross-section of the shape of an inverted U, the top D thereof being semicircular in shape and the sides E extending perpendicularly downward from the ends of the semicircle D. The U-shaped opening F within the arm B extends forward inside the jaw A, where it is closed by an end G, through which there is a circular opening g. The U-shaped opening F is enlarged at F' on its upper surface under the jaw, and on the sides E, under the jaw A, are rectangular raised surfaces E'.

Having thus described my design for a vise-jaw, what I claim is—

The design for a vise-jaw substantially as shown and described.

In testimony whereof I affix my signature in presence of two witnesses.

HENRY F. RENNER.
